CLAIM

The ornamental design for a phone case, as shown and described.

DESCRIPTION

FIG. 1 is a front perspective view of a phone case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear and right-side perspective view thereof showing the ring stand in an extended state; and,

FIG. 10 is a rear, left-side, and bottom perspective view thereof showing the ring stand in an extended state.

The broken lines in the drawings illustrate the portions of the phone case, which form no part of the claimed design.

1 Claim, 10 Drawing Sheets
